CAN SERVER

Corliss L. Weltner, Parkersburg, W. Va., assignor
to The Huffman Manufacturing Company,
Dayton, Ohio, a corporation of Ohio

Application November 21, 1933, Serial No. 699,018

14 Claims. (Cl. 221—23)

This application is a continuation in part of my prior application for an Oil can server, Serial No. 679,114, filed July 5, 1933, and like that application relates to can servers.

5 One object of the invention is the provision of a can server capable of perforating the can in an operation which requires the use of but one of the operator's hands and which will leave the other hand free to manage the spout of the 10 device.

A further object is to provide a device of this class which will make unnecessary the usual valve which is ordinarily provided to control the discharge of fluid.

15 A further object is to provide a novel form of knife for puncturing the can.

A further object is to provide a novel method and means for simultaneously puncturing the top and bottom of a can.

20 Other objects and advantages will be apparent from the following detailed description, the appended claims and the accompanying drawings forming a part of this specification.

In the drawings:

25 Fig. 1 is a vertical sectional view of a device embodying the present invention, and showing a punctured can therein and with a portion of the can broken away to reveal the operation of the knife;

30 Fig. 2 is a horizontal sectional view taken substantially on the line 2—2 of Fig. 1;

Fig. 3 is a sectional view showing a modified arrangement of the can puncturing means; and

35 Fig. 4 is a horizontal section on line 4—4 of Fig. 3.

In the drawings wherein like reference characters have been used throughout to designate like parts, 10 indicates the body of a cylindrical support or can container having a slightly flared 40 bottom portion 11 and a top edge 9. A funnel-like floor is formed at the juncture of the body 10 and the flared portion 11 and has its greatest depth adjacent the front of the support where it is provided with an opening 13 in which is fitted 45 in any suitable manner the terminal end 14 of the usual flexible discharge spout. The body portion 15 of the spout is flexible as is usual with filling cans generally and the usual non-flexible discharge nozzle 16 is provided at the free end of 50 the spout. The spout is normally retained in upright position by a fixed hook or clip 17 which is secured to the forward portion of the upper edge 9 of the body 10 and which engages the nozzle 16 in any suitable manner.

55 A rigid handle member 8 is secured firmly to

the rear portion of the body 10, as at 18, by solder or like fastening means and comprises an upright portion 7 which is secured to the body 10 as aforesaid and which extends somewhat above the upper edge 9 of the body 10. The top of the 5 handle member 8 comprises a rearwardly and horizontally extending portion 21 preferably integral with the upright portion 7. The portion 21 has a slot 21a running lengthways thereof and is further provided on either side of the slot 21a 10 with a pair of upwardly extending ears 22 which are pierced as at 23. The grip portion 20 of the handle member 8 is formed by a downward and outward continuation of the portion 21. At its lower end the grip 20 is integral with a substantially horizontal bottom portion 19 which extends inwardly beneath the lower end of the upright portion 7 and is soldered or otherwise secured thereto. The portion 19, as shown at 33, extends through the juncture of the body 10 and the flared portion 11 and into and across the interior of the support, being positioned, as shown, somewhat above the funnel-like floor 12 and extending to the opposite side of the support where it is secured to its wall as at 33a. A slightly raised 25 abutment or seat 35a for a resilient member or spring 35 is formed on the extension portion 33 in such position that the spring is adapted to engage the substantial center of a can 40 received by the support. The spring 35 is suitably secured to the 30 seat 35a by bolt 36 or the like. A can-puncturing knife 37 is removably mounted adjacent the forward end 33a of the extension portion 33 by means of the screws 37a which are threaded in the extension portion.

35 It will now be apparent that the rigid extension portion 33 forms a substantially unyielding base for the knife 37. The knife 37 is V-shaped in plan and has its apex 39 pointing toward the forward wall of the body 10. In this position 40 it will be adapted to cut an opening in the forward portion of the can bottom. From the apex 39 the cutting blade slopes downwardly and rearwardly sharply to provide a sharp point at the said apex. The free ends of the V well below 45 the apex are connected by a cross bar 38 which is blunt on its upper surface and which serves to roll back the cut stock 41 of the can bottom after the same has been cut by the cutting edge of the knife and which insures a wide and substantially 50 unobstructed opening in the can bottom. As seen in the drawings the cut stock 41 is rolled upwardly and entirely out of the way.

The can 40 of oil or other material to be dispensed is forced downwardly on the knife 37 by 55

mechanism that can be readily manipulated by the operator's hand while grasping the supporting handle, leaving the other hand free to manage the spout. This downward forcible movement of the can is effected by an arm 26 which is movable towards and away from the axis of the can support so that the grip of the operator while holding the handle 20 can be utilized to force the arm towards the handle. As shown, the arm 26 forms the long arm of a bell crank 25 which has a short arm 27 swingably secured at its fulcrum between the ears 22 of the top portion 21 of the handle member 8 by means of a pin 24 which extends through the pierced portions 23 of said ears. The long arm 26 of the crank extends downwardly through the slot 21a in the portion 21 and is normally retained in a forward position by suitable spring means as 31 which may be suitably secured to the upright portion 7 at 32 and to the arm 26 at 31. Any means such as the flat plate 29 may be secured to the lower portion of the arm 26 to protect the operator's fingers against cutting when the said arm is swung rearwardly against the action of the spring 30. The short arm 27 extends forwardly over the top of a can 40 and is provided at its free end with a depending punch 28 for piercing the top of the can for the purpose of admitting air to the can and thus expediting the flow of the liquid from the aperture pierced in the bottom by the knife 37. A depending lug 28a formed on the short arm 27 and spaced slightly from the punch 28 provides a notch or space adjacent thereto for receiving the upper rim of the can 40, and to add in maintaining the same in a proper position for the puncturing operation.

The operation of the device is as follows:

With the long arm 26 of the bell crank 25 in its normal forward position, and the short arm consequently raised, a can 40 is inserted in the support 10 which is of a diameter slightly larger than the can to be opened. When the can bottom strikes the apex 39 of the knife the operator grasps the long arm 26 of the crank and swings it rearwardly. This action causes the short arm 27 to swing downwardly in an arc until the punch 28 strikes the top of the can 40, the upper rim of the can being seated against the under surface of the short arm 27 between the punch 28 and the lug 28a. The can is now securely held in place within the body 10. The spout is now disengaged from the member 11 and held in a proper filling position by the operator's free hand. The operator now continues the pressure on the arm 26 while holding the handle in his grasp, causing the punch 28 to pierce the can top while at about the same time or immediately after piercing the top the can is forced downwardly on the knife 37 and pierced at its bottom. As the spout is already in the filling position, inserted in the filling aperture of a suitable receptacle (not shown), the fluid within the can immediately flows from the can into the receptacle without the additional operation of opening a valve. As the short arm 27 swings downwardly and outwardly, the punch 28 describes a similar arc and consequently a space 42 is provided at the end of the cut which is sufficient to admit the necessary air into the can.

The spring 35 on the extension 33 serves to force the pierced can upwardly after it is pierced and thus facilitates the removal of the same, and also withdraws the knife from the aperture and allows the liquid to flow freely therethrough. The force applied to the upper rear part of the can

at its top and to the forward portion of the can bottom is exerted and assumed by the punch mechanism and the knife 37 both of which are supported by the rigid handle member 8 or a rigid extension thereof so that the body portion and bottom of the support 10 are free of large strains and may be made of sheet metal.

It will be noted that it is not necessary to place the can on a rigid support and press the can downwardly on the knife to accomplish the piercing operation. Nor is it necessary for the operator to perform any unusual or unorthodox movements. By positioning the long arm 26 of the crank 25 within the circle of the handle, it is a simple matter for the operator to extend his fingers and grip the long arm for the operation. On account of the length of the long arm 26 no great strength on the operator's part is required, and much time is saved thereby. Also, by positioning the knife in the manner shown on a support above the floor 12, no pressure on the floor occurs, but the liquid can flow freely to the discharge conduit and all of the liquid is readily drained from the can while the support is held upright or slightly inclined forwardly.

A modification of my can bottom puncturing mechanism is seen in Figs. 3 and 4. Here it will be noted that the arm 133 does not extend entirely across the support and that the resilient member 135 is secured on the free end 134 by means 136. It is also to be noted that in this form of the invention the knife 137 is made integral with the arm 133 and is positioned thereon between the resilient member 135 and the rear wall of the support although it is also to be understood that the knife could be positioned on the wall 110 without departing from the spirit of my invention. The arrangement of the handle member and operating mechanism and the remaining parts of the device shown in Figs. 3 and 4 corresponds to the construction shown in Figs. 1 and 2.

While the drawings show and the specification describes what is now considered to be the preferred embodiments of my invention, it is understood that I do not expressly limit myself to the precise structures shown and described because it is apparent that my invention is capable of other expressions and embodiments within the scope of the appended claims.

What is claimed is:

1. In a can server, a support for a can, a fixed carrying handle member for said support, a bottom for said support having a discharge spout connected to the forward portion thereof, and a plurality of can piercing means provided on said handle member for simultaneously piercing the forward portion of a bottom of a can and the rear portion of the top of a can.

2. In a portable can server, a support adapted to receive a can of material, a carrying handle rigid with said support, said support having a bottom provided with a discharge conduit, a knife carried in said support and adapted to pierce the bottom of a can forced downwardly in said support, and means adapted for operation by the hand when grasping the handle for forcing the can against the knife.

3. In a portable can server, a support adapted to receive a can of material, a carrying handle rigid with said support, said support having a bottom provided with a discharge conduit, a knife carried in said support and adapted to pierce the bottom of a can forced downwardly in said support, means adapted for operation by the hand

when grasping the handle for forcing the can against the knife, and means operated thereby for piercing an upper portion of the can.

4. A can server comprising a can support adapted to receive and house the lower portion of a can, said support having a bottom provided with a discharge spout, a knife mounted in said support in position to pierce the bottom of a can forced downwardly thereagainst, a handle fixed to said support, an operable member provided adjacent said handle in position for operation by the hand when grasping the handle, a can top piercing member, and means connecting said top piercing member and said operable member.

15 5. In a can server, a can support, a handle for said support, said support having a bottom provided with a discharge conduit, means rigid with said handle and projecting into said support, and a knife provided on said means.

20 6. In a can server, a support for a can, a handle for said support, said support having a bottom provided with a discharge spout, a member rigid with said handle and extending into said support, a knife on said member adapted to pierce the bottom of the can forced downwardly in said support, and means carried by said handle for piercing the top of a can and for forcing the can downwardly against said knife.

25 7. In a can server, a can support, a handle for said support, said support having a bottom provided with a discharge conduit, means rigid with said handle and projecting into said support above said bottom, a knife fixed to said means and adapted to pierce the bottom of a can forced downwardly thereagainst, and mechanism operable from a point adjacent said handle for forcing a can against said knife.

30 8. In a can server, a support for a can, a handle for said support, said support having a bottom provided with a movable discharge spout in constant communication with the space above said bottom, a member rigid with said handle and extending into said support, a knife on said member adapted to pierce the bottom of the can forced downwardly in said support, and means movably mounted on said support for piercing the top of a can and for forcing the can downwardly against said knife.

35 9. In a can server, a support for a can, a handle for said support, a bottom for said support having a discharge spout connected thereto, an upstanding V-shaped knife for piercing the bottom of a can rigidly carried by said support slightly above the bottom thereof, a blunt bar connecting the free ends of said knife for rolling back the cut stock of said can bottom, and means associated with said handle for simultaneously piercing the top of said can and forcing the can downwardly onto said bottom piercing means.

40 10. In a can server, a support for a can, a handle for said support, a bottom for said support having a discharge spout connected thereto, means for piercing the bottom of a can, said means being located slightly above the bottom of said support, means carried by said handle for simultaneously piercing the top of a can and forcing the can downwardly onto said bottom piercing means, and means comprising a coiled spring adjacent said bottom piercing means for forcing the can out of engagement with the same after the can is pierced.

45 11. In a can server, a support for a can, a looped handle for said support, a bell crank swingably connected to the top of said handle and having one arm extending downwardly adja-

cent the gripping portion of the same, the second arm of said crank extending forwardly over said support and adapted for piercing the top of a can and forcing the can downwardly in said support, a bottom for said support having a discharge 5 spout connected thereto, and a knife rigidly carried by said support adjacent the bottom thereof and adapted to pierce the bottom of a can when the same is forced downwardly thereon by the action of said shorter arm of said crank.

10 12. In a can server, a cylindrical support for a can, a looped handle for said support and extending above said support, a slot in the upper portion of said handle, upstanding pierced ears on either side of said slot, a bell crank swingably mounted at its fulcrum between said ears in the pierced portions thereof and having one arm extending downwardly through said slot within said handle and adjacent the gripping portion thereof, the other arm of said crank being substantially 20 shorter than said first arm and extending forwardly over said support and having a depending punch on its free end for piercing the top of a can while forcing the can downwardly into said support, means adjacent said punch for engaging 25 the rim of a can, the lower portion of said handle being extended into said support through the side wall thereof and providing a substantially rigid seat for an upwardly extending V-shaped knife for piercing the bottom of a can, a blunt cross 30 bar connecting the free ends of the legs of said knife to engage the base of the cut stock of the can bottom and force said cut stock upwardly when the can is forced downwardly on the knife by the action of the shorter arm of the crank, an 35 upstanding coiled spring on said seat to disengage the can from said knife when pressure on said can is released, and discharge means for the can contents located below said knife.

13. In a can server, a cylindrical support for 40 a can, a looped handle for said support and extending above said support, a slot in the upper portion of said handle, upstanding pierced ears on either side of said slot, a bell crank swingably mounted at its fulcrum between said ears in the 45 pierced portion thereof and having one arm extending downwardly through said slot within said handle and adjacent the gripping portion thereof, the other arm of said crank being substantially shorter than said first arm and extending forwardly over said support and having a depending 50 punch on its free end for piercing the top of a can while forcing the can downwardly into said support, the lower portion of said handle being extended into said support through the side wall 55 thereof and providing a substantially rigid seat for an upwardly extending V-shaped knife for piercing the bottom of a can, a blunt cross bar connecting the free ends of the legs of said knife to engage the base of the cut stock of the can 60 bottom and force said cut stock upwardly when the can is forced downwardly on the knife by the action of the shorter arm of the crank, an upstanding coiled spring on the free end of said seat adjacent said knife to disengage the can 65 from said knife when pressure on said can is released, and discharge means for can contents located below said knife.

14. In a portable can server a knife adapted to pierce the lower end of a can forced thereagainst, 70 said knife having a substantially V-shaped upstanding cutting edge and a blunt bar connecting the free ends of the knife below the apex of the V for rolling back the cut stock of a can bottom.
